US00D785017S

(12) **United States Design Patent** (10) Patent No.: **US D785,017 S**
(45) Date of Patent: ** Apr. 25, 2017

(54) **DISPLAY SCREEN OR PORTION THEREOF WITH GRAPHICAL USER INTERFACE**

(71) Applicant: **Leauto Intelligent Technology (BEIJING) Co. Ltd.**, Beijing (CN)

(72) Inventors: **Lei Wang**, Beijing (CN); **Fan Yang**, Beijing (CN); **XiuBin Yang**, Beijing (CN); **Ting Wu**, Beijing (CN)

(73) Assignee: **Leauto Intelligent Technology (Beijing) Co. Ltd.**, Beijing (CN)

(**) Term: **15 Years**

(21) Appl. No.: **29/505,566**

(22) Filed: **Dec. 23, 2015**

(30) **Foreign Application Priority Data**

Oct. 26, 2015 (CN) 2015 3 0416834

(57) **CLAIM**

The ornamental design for a display screen or portion thereof with graphical user interface, as shown and described.

DESCRIPTION

FIG. 1 is a front view of a display screen or portion thereof with graphical user interface, showing my new design; and, FIG. 2 is a second embodiment thereof.

The broken lines showing a device illustrates environment, whereas the broken lines showing a display screen and portions of the graphical user interface illustrate portions of the article. None of the broken lines form part of the claimed design.

1 Claim, 2 Drawing Sheets
